UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,986, dated July 1, 1890.

Application filed April 15, 1890. Serial No. 348,107. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 The drawing represents a side elevation of a cane or umbrella handle embodying my improved design.

15 A is the vertical body part, and branches at the top to each side in the parts B, which at the extreme lateral ends turn upward slightly. The parts A B are formed with upwardly running ribs G, terminating in a rounded top and forming in effect an oblong basin, in which is set the top piece C, made with a plain

upper surface and shaded sides D. The part 20 C is slightly curved and has its sides turned up to points, as at H. The lower part of the body A terminates in the annular band I, having a plain lower edge and a shaded junction with the ribs of the body part. 25

The handle may be of any suitable material.

Having now described my new design, what I claim as new, and desire to secure by Letters Patent, is—

30 The design for umbrella or cane handles, substantially as herein described and shown.

In testimony of which invention I have hereunto set my hand.

HENRY O. SCHMIDT.
